Application June 2, 1936, Serial No. 83,024

9 Claims. (Cl. 263—46)

This invention relates to furnaces, and it is exemplified herein as involving improvements in arches used as covers for "soaking pits".

It is an object of the invention to provide a soaking pit cover with low density ceramic refractory elements of high heat insulating capacity so that heat losses will be minimized.

It is also an object of the invention to provide a portable arch or soaking pit cover which will have a refractory lining capable of withstanding the high temperature gases and flames which are necessary in the operation of a soaking pit, and at the same time having such a low weight per unit of furnace face that soaking pits of 15 wide cross section can be advantageously closed by a unitary structure.

In the use of soaking pits the portable arches which constitute their covers are arranged to be shiftable to and from a position over the top of the furnace pit. For this purpose, some arches are mounted on motor driven carriages operating along tracks which have spaced depressions in which the wheels of the carriage naturally tend to become seated when the carriages are moved toward their operative positions over the furnaces, or pits. When the wheels of a carriage drop into these depressions the marginal parts of the cover contact with sand or similar granular material which has been spread around the top of the soaking pit to form a flame or gas seal. These parts are thus subject to repeated impacts and considerable abrasion during the normal use of the soaking pit. Not only must they have sufficient durability or mechanical strength to withstand such repeated impacts and abrasions, but they must also be strong enough to support the weight of the arch in the event that foreign bodies or excessive amounts of sand occur around the tops of the 40 soaking pits.

If the entire arch was faced with refractories of high enough density to adequately withstand the above indicated punishment, the weight of the arch would be excessive. Furthermore, in 45 connection with soaking pits of large cross section, the weight of the steelwork required to support such high density refractories would be excessive. By way of an example of such high density refractories as are referred to herein, 50 ordinary firebrick weighing about 130 lb. per cubic foot are considered to be of high density. The low density refractories are considered to be those which have a density of from $\frac{1}{3}$ to $\frac{1}{2}$ that of such firebrick.

55 This invention solves the above indicated prob-

lem by providing a soaking pit cover, the major portion of which presents a furnace face formed by low density refractories of high heat resisting and high insulating capacities. With such a construction the arch can cover a wide expanse at the top of the soaking pit without requiring an excessively heavy steel supporting framework. Furthermore, heat losses are minimized and better working conditions are promoted by reason of the insulating capacity of the low density refractories. The invention contemplates that the main furnace face portion of the arch shall be encircled by refractories of higher density which can successfully withstand the severe condition to be met in the operation of soaking pits. Their resistance to abrasion is high and they are not easily broken by blows which soaking pit covers may receive during the operation of the cranes which remove heavy ingots from the soaking pit or position them therein. Such actions occur due to the necessity of maintaining the ingots at a high temperature, and the desire on the part of the operator to move the ingots quickly in order that the ingots remaining in the soaking pit shall not have their temperatures excessively lowered by the temporary removal of the cover.

Other objects of the invention will appear as the accompanying description proceeds.

The invention will be described with reference to the attached drawings, in which:

Fig. 1 is a view in the nature of a vertical section indicating the carriage wheels for supporting the arch, and showing the relationships of the refractories to the supporting framework.

Fig. 2 is a view in the nature of a vertical section taken along a plane at right angles to the plane of Fig. 1, and indicated by the line 2—2 of Fig. 1.

Fig. 3 is a partial plan broken away at one corner to show the relationships of the marginal refractories to the inner elements.

Fig. 4 is a detailed view in the nature of a perspective showing the manner in which the inner refractories are suspended from the supporting steelwork.

Fig. 5 is a detail view in the nature of a perspective indicating the manner in which some of the marginal refractories are secured to the steelwork.

Fig. 6 is a detail view in the nature of a horizontal section showing a modification by which some of the marginal refractories are supported from the steelwork. This view is taken on the line 6—6 of Fig. 7.

Fig. 7 is a detail view in the nature of a vertical section taken on the line 7—7 of Fig. 6, and further showing how the marginal refractories of Fig. 6 are supported.

5 In the drawings, Fig. 2 shows the top of a soaking pit 10 having side walls 12 and 14 over the tops of which sand is spread to form a gas and flame seal as shown at 16 and 18. In some instances this sand also affords a support for the 10 cover.

The soaking pit cover indicated generally by the numeral 20 contacts with the sand seals as indicated, and may be portably supported (in its inoperative position) by a superposed carriage 15 which includes the axle 22 and the wheels 24 and 26. The latter are arranged to run upon tracks 30 and 32 having the depressions 34 and 36 so arranged that the wheels drop into them as the cover approaches its operative position.

20 The cover, as an entirety, may be supported from the carriage in any suitable manner. The former involves a steel frame consisting of the beams 40 and 42 connected by the transverse channels 44 and 46 and the I beams 48 and 49. 25 Brick supporting angles 50 and 52 extend across the arch, with their ends supported upon angles 54 and 56 which are rigidly secured to the beams 42 and 40.

20 The angles 50 and 52 support the low density 30 refractories 58 in the manner indicated in Fig. 4 of the drawings. As shown, these refractories are apertured to receive the horizontal suspension rods 60 and they are recessed at their upper ends to receive the eye-bolts 62 which extend through 35 openings in the horizontal flanges of the angles 50 and 52. These eye-bolts may be maintained in their operative position by cotter pins 65 extending through openings in their stems, as shown. As indicated in Fig. 3 of the drawings, 40 the rods 60 are rather short. That is, they do not extend all the way across the soaking pit cover, and are so arranged that a small number of the refractories 58 may be removed as a unit for the purposes of repair and replacement.

45 Fig. 2 shows the high density refractories 64 as extending below the furnace face formed by the inner refractories 58, and abutting at their tops against the horizontal portions of the angles 54 and 56. They are rigidly secured to the beams 50 42 and 40 by bolts 66 which hold them tightly in position with compressible insulating material 68 interposed with reference to the refractories 64 and the beams.

55 Instead of securing the high density refractories 64 as indicated in Fig. 2, they may be secured in the manner indicated in Figs. 6 and 7. As here shown, T members 70 are rigidly secured to the inner faces of the beams 42 and 40 and the high density refractories 72 are formed with 60 lateral recesses and slots so that they may be positioned over the T members 70 and thereafter dropped into their operative positions indicated in Fig. 7.

65 Figs. 2, 5, and 7 indicate other marginal refractories 74 secured to the horizontal flanges of the beams 42 and 40 so as to protect the latter against the flames from the soaking pit. These refractories are secured to the lower horizontal flanges of the beams in the manner indicated in Fig. 5. 70 As here indicated, refractories 74 are apertured to receive horizontal rods 76 secured to the flanges 78 by eye-bolts 80 which are positioned within recesses in the refractories, as shown.

Figs. 1 and 3 show the high density refractories 75 which are arranged along the remaining margins

of the arch. These refractories 80 may be inter-fitted as indicated at 82 and 84 in Fig. 3 and their suspension rods 86 and 88 are arranged in staggered formation so as to maintain the refractories in their normal alignment against impacts which 5 tend to move them out of their operative positions. The refractories 84, are overlapped along their vertical margins as indicated in Fig. 3, in order to prevent the escape of furnace gases.

While the invention has been described with 10 reference to the particular modifications shown in the drawings, it is to be appreciated that it is not necessarily limited to the particular combinations shown therein. It is, rather, of a scope, commensurate with the scope of the subjoined 15 claims.

What is claimed is:

1. In a soaking pit cover, a portably mounted metallic framework, refractories of low density 20 and high heat resistance forming the main heat resisting portion of the cover, a band of high density refractory elements encircling said portion and adapted to be contacted by sealing material deposited around the top of the soaking pit, and means for detachably securing all of said 25 refractories to said framework.

2. In combination with a furnace having an upwardly presented charging port of large area, a readily removable arch normally closing said port and comprising, relatively low density refractory elements forming the main heat resisting portion of the arch spanning the port, rows of high density refractory elements of high load sustaining capacity positioned at the margins of the arch, steel-work spanning the port, and means 30 for suspending the refractory elements from the steel-work, said high density elements having their lower surfaces extending below the flame face of the main portion of the arch.

3. In combination with a furnace having an 40 upwardly presented charging port of large area, a readily removable arch normally closing said port and comprising, relatively low density refractory elements forming the refractory body of the main portion of the arch spanning the port, rows 45 of high density refractory elements of higher load sustaining capacity positioned at the margins of the arch, steel-work spanning the port, and suspending means including upper bars bridging the steel-work and lower supports interengaged with 50 the refractory elements.

4. In combination with a furnace having an upwardly presented charging port of large area, a readily removable arch normally closing said 55 port and comprising, relatively low density refractory elements forming the main portion of the arch spanning the port, rows of high density refractory elements of high load sustaining capacity positioned at the margins of the arch and arranged to take at least a part of the load of 60 the arch, steel-work spanning the port, and means for suspending the refractory elements from the steel-work, said steel-work including members which bear directly against the high density refractory elements.

5. In combination with a furnace having an upwardly presented charging port of large area, a readily removable arch normally closing said 70 port and comprising, relatively low density refractory elements forming the main portion of the arch spanning the port, rows of high density refractory elements of high load sustaining capacity positioned at the margins of the arch, and means for suspending the refractory elements from the 75

steel-work, there being two rows of high density refractory elements at opposite margins of the arch, with one row of said elements of each side having their wider faces presented toward the walls forming the furnace opening to permit the port to be closed with a wide sand seal.

6. In combination with a furnace having an upwardly presented charging port of large area, a readily removable arch normally closing said port and comprising, relatively low density refractory elements forming the refractory body of the main portion of the arch spanning the port, rows of high density refractory elements of high load sustaining capacity positioned at the margins of the arch and arranged so that they may take at least a part of the load of the arch, steel-work spanning the port, and means for suspending the refractory elements from the steel-work, said high density refractory elements having interengaging portions.

7. In combination with a furnace having an upwardly presented charging port of large area, a readily removable arch normally closing said port and comprising, relatively low density refractory elements forming the main portion of the arch spanning the port, rows of high density refractory elements of high load sustaining capacity positioned at the margins of the arch and arranged to take at least a part of the load of the arch, steel-work spanning the port, and means for

suspending the refractory elements from the steel-work.

8. In a soaking pit cover, a portably mounted metallic framework, ceramic refractories of low density and high heat resistance forming the main refractory body of the cover, a band of high density refractory elements encircling said refractories and adapted to be positioned out of the zones of highest temperature and to contact with sealing material deposited around the top of the soaking pit, and means for detachably suspending all of said refractories from said framework, so that the elements of said encircling band shall be maintained in abutting relationship to said low density refractories. 15

9. In a furnace cover, a portably mounted metallic framework, ceramic refractories of low density and high heat resistance forming the main refractory body of the cover, high density refractory elements bordering said refractories and adapted to be positioned out of the zones of highest temperature and to contact with sealing material deposited around the top of the furnace, and means for detachably suspending said refractories from said framework in groups, said high density refractories being shielded by the walls of the furnace. 20 25
